COMBINED CONFERENCE TABLE AND DESK

Norman E. H. Deletzke, Jr., 224 Sheridan Road,
Kenilworth, Ill.

Filed Jan. 5, 1961, Ser. No. 63,458

Term of patent 14 years

(Cl. D33—7)

FIGURE 1 is a bottom plan view of a combined conference table and desk, showing my new design and showing the pitched and curved outer end faces of the desk drawers;

I claim:

The ornamental design for a combined conference table and desk, substantially as shown.
